CLAIM

The ornamental design for a photosensitive drum for process cartridge for image forming apparatus, as shown and described.

DESCRIPTION

FIG. 1 is a front view showing my new design.
FIG. 2 is a back view thereof.

FIG. 3 is a top view thereof.

FIG. 4 is a bottom view thereof.

FIG. 5 is a left side view thereof.

FIG. 6 is a right side view thereof.

FIG. 7 is a perspective view thereof.

FIG. 8 is an enlarged left side view thereof; and,

FIG. 9 is an enlarged right side view thereof.

FIG. 8 is an enlarged view of FIG. 5; FIG. 9 is an enlarged view of FIG. 6.

The portions of the photosensitive drum for process cartridge for image forming apparatus shown in broken lines form no part of the claimed design.
